UNITED STATES PATENT OFFICE.

FERDINAND BUCHHOP, OF NEW YORK, N.Y., ASSIGNOR TO THE MEYROWITZ MANUFACTURING COMPANY, A CORPORATION OF NEW JERSEY.

LENS-GRINDING IMPLEMENT.

937,763.

Specification of Letters Patent. Patented Oct. 26, 1909.

Application filed December 16, 1908. Serial No. 487,810.

To all whom it may concern:

Be it known that I, FERDINAND BUCHHOP, a citizen of the United States, residing at the city of New York, in the borough of Brooklyn and State of New York, have invented certain new and useful Improvements in Lens-Grinding Implements, of which the following is a full, clear, and exact description.

10 This invention relates to tools or apparatus employed in grinding the lens blanks for "Kryptok" bifocal lenses. In the manufacture of these lenses a depression or concavity is formed eccentrically in the surface 15 of a major lens blank at a point which must be accurately predetermined. Afterward a minor lens of glass of higher refractive power is fused into said depression or cavity, and the entire lens blank then ground away 20 and trimmed to form a lens for eyeglasses or spectacles in which a different focal length is obtained for distant vision from that obtained in reading, the line of vision being downward in the latter case and corresponding 25 to the location of the minor lens blank. The nature of these processes and the subsequent character of use of the glasses necessitate a somewhat precise location and formation of the said cavity or depression.

30 It is the main object of my invention to provide a combination of tool and work-holding device which is adapted to do this work easily and expeditiously for a plurality of lens blanks at a single operation.

35 The nature of the process and the characteristics of the tools, etc., employed, embody several theoretical principles, as later pointed out.

40 The structural characteristics of the invention will be first considered, having reference to the accompanying drawings which illustrate preferred embodiments of the invention.

45 In the drawings: Figure 1 is a sectional view showing a lens blank or work-holder and grinding head, as employed in forming the depressions or cavities of Kryptok lenses in accordance with this invention; Fig. 2 shows a similar couple adapted for a different radius of curvature of the depression; Fig. 3 is a bottom plan view of the holder; Figs. 4 and 5 are sectional views showing slightly modified constructions; Fig. 6 is a 50 sectional view showing a further modifi-

cation, and Fig. 7 is a section on the line 55 VII—VII of Fig. 6.

1 designates a frame having a central body 2 with a plurality of arms 3. These arms have inner faces adapted to support lens blanks in planes 4, the essential characteristics of which are that they all radiate at exactly equal angles from a common axis and vertex. For this purpose each arm has seats 7 and 9 to support the lens blank and which are separated by an intermediate recess 6, 65 and also a stop or shoulder 5 which fixes the radial location of the blank. The construction of these various features is based on theoretical or mathematical considerations as follows:

70 The depressions or cavities C of the blanks A, being spherical in curvature, are necessarily ground by a tool B of correspondingly spherical form or having a fixed radius of curvature at all points. If any number of 75 glass bodies or blanks greater than two are fixed in any holder and simultaneously applied to the tool B, they will be simultaneously ground with lens surfaces. This principle is of universal application to spherical 80 lens grinding process and is of obvious applicability when the entire surface of the blank is ground away to the prescribed curvature, it being merely necessary to continue the grinding until a surface of more 85 than adequate dimensions has been ground away on each blank. In grinding Kryptok lenses, the conditions are different, however, calling for a depression which is not only of certain curvature, but which is located in a 90 predetermined position on a blank of prescribed form, and which must have a definite diameter determined by the depth to which the grinding is carried. These conditions make it necessary to provide for the various 95 factors in some other way than merely cementing the blanks more or less carelessly in any form of concave holder in the usual manner employed for ordinary lens work.

To illustrate by a practical example, it may 100 be assumed that depressions having a radius of curvature of one and thirteen sixteenths inches and a diameter across of three-quarters of an inch, are to be formed in lens blanks of the ordinary sort cut from plate 105 glass to a square outline measuring about one and three-quarters inches on each side, the depressions being centered symmetrically

on one diameter, and one-half an inch from a side edge on the other diameter. The blanks might, of course, be independently embedded in cement by independent measuring and obtain the foregoing results, but the time and care which would be necessary would be almost prohibitive for commercial purposes. I make use of the following principles to expedite the location of the blanks, 10 making the operation as simple or even simpler than is the case in ordinary lens grinding processes.

A sphere coincident with the surface of the tool B may be circumscribed by an equilateral pyramid in which case the planes of each of the faces will be tangent to the sphere. The points of tangency will furthermore be located at equal and fixed distances from the apex of the pyramid. These 20 distances are equal, but vary with the radius of the tool or sphere and the vertical angle of the pyramid. In order to grind lens blanks with depressions in the manner described, they may be faced in the planes of such a pyramid to determine their position in a work holder. There are other geometrical relations by which the lenses might be located and centered, for example, by seating them inside a spherical surface of 30 different curvature from the curvature of the tool, but I have found that the pyramid relation gives a very useful and practical solution for perfectly mounting the lens blanks, as it enables every factor to be taken into 35 account in a very easy way. The lens blanks being square and of plate glass of substantially uniform thickness, permits their being assembled on rigid seats which fix the planes of their faces to be ground, accurately in the 40 planes of such a pyramid, and in this relation they may be easily located by lateral stops or shoulders on center lines of the pyramid faces and at exactly located distances from the pyramid apex. Not only, 45 therefore, are the lens blanks easily located in all respects, but the grinding action is insured to proceed in a way which is easily mathematically predetermined for a particular holder and tool.

50 In the example above noted a pyramid would first be theoretically determined upon of such an angle as would permit an assembling of the square blanks with their side edges at a distance of about one and one-quarter inches from the pyramid apex, which is substantially uniform distance for 55 all cases, being as compact a disposition of the blanks as possible, limited by the proximity of their adjacent corners. This compact disposition is desirable as it makes the 60 pressure of the grinding operation more nearly normal to the surface to be ground for each blank. These conditions being determined upon, an easy mathematical computation fixes the vertical angle of the pyra-

mid at exactly 92° . A lens holder is therefore adopted which will fix the planes of the blanks to be ground in the faces of the foregoing pyramid at a distance of one and one-quarter inches from its apex, the planes being determined by rigid metallic seats of the holder which are adapted to be easily fitted to suit the particular vertical angle of the pyramid.

70 Referring now again to the practical construction, Figs. 1 and 2 show the adaptation of the lens holder to two different grinding heads B and B', respectively. Grinding head B has a radius of curvature of one and thirteen-sixteenths inches and grinding head B' has a radius of curvature of one and eleven-sixteenths inches. The ledges 5 being located at a substantially constant point in accordance with the foregoing principles for all cases, it follows that the planes 4 in Figs. 80 1 and 2 (which are parallel with the front faces of the blanks owing to the latter being of plate glass) should make angles of

$$\tan^{-1} \frac{1 \frac{13}{16}}{1 \frac{1}{4} + 1/2} = 46^\circ$$

90

and

$$\tan^{-1} \frac{1 \frac{11}{16}}{1 \frac{1}{4} + 1/2} = 44^\circ$$

95 respectively, with the common axis, the planes radiating from a common vertex. The ledge 9 is made thick enough or the depth of the recess 6 great enough to permit the ledge 9 being merely filed down with a simple bevel angle-gage so that the plane determined by this ledge and the support 7 is exactly 46° in Fig. 1 and 44° in Fig. 2. The machining being accomplished in this simple way, it is merely necessary to mark the holder to accord to the particular grinding head for which it was designed, and thereafter any comparatively unskilled operator can easily and expeditiously assemble the lens blanks against the seats 5, 7 and 9 and pour the usual cement into the recess 6 and 100 insert the apparatus in a grinding machine without further attention, whereupon the lens blanks will be properly ground with depressions exact in all matters of form, 105 curvature, diameter and location, these factors all being determined by the action of the machine on account of the foregoing theoretical principles with respect to the pyramid which is virtually formed in conjunction with the spherical tool of determined radius.

110 In Figs. 4 and 5 the planes are determined and varied in a different way. In Fig. 4 the holder has pivoted arms 10, the position of which is fixed by adjustment screws 12 and which have flat faces 11 to receive the lens blanks. In Fig. 5 pivoted arms 13 are provided with stems 14 engaged by a central plug 15, the position of which is varied by a 115 threaded stem 16 and lock nut 17. 18 de-

125

130

135

notes blade springs to keep the arms fixed against the plug 15.

In Fig. 6 the lens blanks are held against the flat faces of the holder by clamps 20 having bent-over ends 21 to engage the lens blanks and tightened thereon by set screws 22.

Having described my invention, I claim:

1. A lens grinding implement comprising a work holder having a plurality of seats 10 therein for lens blanks in combination with a spherical grinding head of such curvature that it will be tangent to eccentric points on all of the lens blanks.

2. A lens grinding implement comprising 15 a holder having seats for a plurality of lens blanks, in combination with a grinding head of a spherical curvature tangent to the surfaces of the lens blanks at points offset from the centers of said blanks by a predetermined distance.

3. A lens grinding implement comprising 25 a holder having seats for a plurality of lens blanks, in combination with a grinding head of a spherical curvature tangent to the surfaces of the lens blanks at points offset from the centers of said blanks by a predetermined distance toward a common point or vertex.

4. A lens blank holder for grinding processes, comprising a frame having arms projecting symmetrically at equal angles from a common central axis and vertex and having 30 interior faces on which the lens blanks are accurately seated in the planes of said angles.

5. A lens blank holder for grinding processes, comprising a frame having arms projecting symmetrically at equal angles from 35

a common central axis and vertex, said arms having interior faces on which the lens 40 blanks are accurately seated in the planes of said angles and having lugs or shoulders to locate said blanks on said faces.

6. A lens blank holder for grinding processes, comprising a frame having arms projecting symmetrically at equal angles from a common central axis, said arms having interior faces with a recess or cavity and adapted to seat lens blanks accurately in the 45 planes of said angles.

7. A lens blank holder for grinding processes, comprising a frame having arms projecting symmetrically at equal angles from a common central axis, said arms having interior faces to seat the blanks accurately in 50 the planes of said angles, and having lugs to position said blanks accurately at equal distances from said axis.

8. A lens blank holder for grinding processes, comprising a frame having arms projecting symmetrically at equal angles from a common central axis, each arm having a ledge and a rounded extremity adapted to position the blanks accurately in the planes 55 of said angles, said arms having a recess between said ledges and said extremities whereby the ledges may be cut away and effect a change in the angles of the lens blanks.

In witness whereof, I subscribe my signature, in the presence of two witnesses.

FERDINAND BUCHHOP.
